UNITED STATES PATENT OFFICE.

CHARLES H. BOYLES, OF SEATTLE, WASHINGTON.

ANCHOR.

1,316,348.

Specification of Letters Patent. Patented Sept. 16, 1919.

Application filed March 22, 1919. Serial No. 284,402.

To all whom it may concern:

Be it known that I, CHARLES H. BOYLES, a citizen of the United States, residing at Seattle, in the county of King and State of Washington, have invented certain new and useful Improvements in Anchors, of which the following is a specification.

This invention relates to anchors constructed of reinforced concrete; and its object is to produce an efficient anchor of this type which may advantageously be used as a substitute for wrought or castmetal anchors.

A further object is to produce an anchor of inexpensive cost and of strong and durable construction.

To these and other ends, the invention consists in the novel construction, adaptation and combination of devices, as will be hereinafter described and claimed.

In the accompanying drawings, Figure 1, is an elevational view showing upon one side the concrete structure and on the other side is shown the reinforcing framework to be embedded in concrete as indicated by dotted lines. Fig. 2 is an elevational view of the upper portion of the reinforcing structure for the anchor shank taken rectangular to Fig. 1. Fig. 3 is a similar view, rectangular to Fig. 1, of the lower part of the anchor. Fig. 4 is a sectional view through 4—4 of Fig. 1. In Figs. 2, 3 and 4 the outlines of the concrete embedding the reinforcing framework is represented by dotted lines. Fig. 5 is a perspective view of one of the frame members.

In said drawings, the reference numeral 5 designates the shank and 6 the arms of a four-fluke anchor consisting of concrete cast about a reinforcing or skeleton frame which is fabricated from iron or steel rods. The shank portion of said frame comprises two rods bent at substantially their midlengths to afford loops 7 engaging the anchor ring 8 and providing from each rod two downwardly extending corner elements 9. These elements are connected by bends 9¹ with hooks 15 extending laterally, as at 11 and 12 (Fig. 4) in converging directions at each side and disposed in planes which are inclined slightly upwardly.

As shown, the parts 11 terminate in ends 11¹ while the associated parts 12 extend to loop 12¹ and thence returning terminate in ends 12² which overlap the ends 11¹, the

adjacent ends thereof being secured together by wire ties 13.

Seated upon parts 11 and 12 of the two above-subscribed hook members are the side portions 14 of a third member having hooks 16 disposed in rectangular relations to the axis of the aforesaid hooks.

The last mentioned member is desirably made from a single rod formed as shown in Figs. 3 and 4, to provide loops 16¹, and have the overlapping ends 16² of the rod secured together by wire ties 17.

Subjacent to the lateral and longitudinal hooks 15 and 16 are two frame members 18, such as illustrated in Fig. 5, formed with loops 19 in their converging outer portions 18¹ and 18² of the respective members.

The members 18 are suspended from the hook elements 15 and 16 by spaced hanger straps 20 formed of rods and connected thereto by wire ties 21.

Straps 22 formed of suitably bent rods having their ends coupled by the wires 23 are employed to unite the elements 9 to which they are connected by means of wire ties 23¹.

Supplementary to the members 18 are rods having upright stems 24 secured by tie wires 25 to one or more of the shank straps 22 and having at their lower ends arms 24¹ 85 which are directed into the space between the upper and lower members of the frame at the front and rear of the same.

The above-described parts are assembled as shown, and an angular shaped fluke-plate 26 is attached to the outer ends of the complementary hooks and ends of members 18 by means of bolts 27 extending within the various hook loops and apertures provided in the plates.

In operation, the reinforcing skeleton framework is placed within a suitable mold into which concrete is deposited to embed the same, except the fluke plates 26 whose upper and lower surfaces are respectively 90 flush with the corresponding surfaces 6¹ and 6² of the anchor arms 6. These fluke plates serve to protect the points of the arms from being broken, and may be replaced when worn.

Except for said plates and a part of the ring 8 which protrudes from the shank, there is no metal exposed.

The various elements of the hook members and the members 18 which are subja-

105

110

cent thereto, are disposed to be in lines adjacent to and approximating the corners of the embedding concrete material. The hook members have their arm elements 15 integral with the shank elements, whereby strength and rigidity is afforded to the lateral arms.

The arm elements 16 at the front and rear, as shown, are connected by tie wires to the hook members, and by extending between the remote ends of the anchor arms, are peculiarly efficient to afford strength and rigidity to the longitudinally disposed arms. These arms are furthermore reinforced by means of the members 24—24¹ whose stems 15 are connected with the hook members and have their parts 24¹ extend into the concrete material of the respective anchor arms.

Reinforcing framework thus constructed provides a skeleton which is peculiarly strong and is adapted to withstand the strains to which the various parts of the anchor are subjected.

What I claim, is—

1. A composite anchor having a shank and arm elements at one end of the shank, skeleton framework formed of interconnected rods, said frame having portions extending into both the arms and said shank, fluke plates bent to angular forms and secured to the extremities of the arm portions of said frame, and a filling of cement within which said frame is embedded, the outer surfaces of said arms in proximity to their points being flush with the outer surfaces.

2. A composite anchor having a shank and arm elements at one end of the shank, a ring at the other end of the shank, skeleton framework formed of interconnected rods, said frame having portions extending into both the arms and said shank and connected to said ring, fluke plates bent to angular forms and secured to the extremities of the arm portions of said frame, and a filling of cement within which said frame is embedded, the outer surfaces of said arms in proximity to their points being flush with the outer surfaces.

3. A composite anchor having shank and

arm elements, two sets of super-arranged rods extending into proximity of the outer ends of the respective arms and constituting a skeleton frame for the latter, the rods of each set being connected together within the respective arms, and a body of concrete within which said frame is embedded.

4. A composite anchor having a shank and arm elements, a skeleton frame composed of rods, a filling of cement embedding said frame, and angular shaped metal fluke plates provided at the points of the respective arms and into which extend the arm elements of said frame.

5. In a composite anchor, a skeleton frame having in the arm sections thereof two sets of rod members disposed at different elevations and terminating in looped portions adjacent to the points of the respective arms, substantially horizontal connections uniting the members of the upper set of members, and substantially upright connections uniting the members of both sets thereof.

6. In a composite anchor, having a shank and a plurality of arms extending from its lower end, a skeleton frame having two sets of members disposed at different elevations, the upper of said sets having elements extending into both the anchor arms and the shank, the lowest set of members being located entirely within the arms, and connections uniting the members of both sets of members.

7. In a composite anchor having a shank and a plurality of arms extending from its lower end, a skeleton frame having two sets of members disposed at different elevations, the upper of said sets having elements extending into both the anchor arms and the shank, the lower set of members being located entirely within the arms, substantially horizontal connecting the members of the upper set of members, and substantially upright connections uniting the members of both sets thereof.

Signed at Seattle, Washington, this 17th day of March, 1919.

CHARLES H. BOYLES.
